(57) **CLAIM**

I claim the ornamental design for a drink bottle, as shown and described.

DESCRIPTION

FIG. 1 shows a perspective top side view of a drink bottle; FIG. 2 shows a front side view of FIG. 1; FIG. 3 shows a rear side view of FIG. 1; FIG. 4 shows a left side view of FIG. 1; FIG. 5 shows a right side view of FIG. 1; FIG. 6 shows a top view of FIG. 1; and, FIG. 7 shows a bottom view of FIG. 1.

The broken lines in the drawings depict portions of the drink bottle that form no part of the claimed design.
